UNITED STATES PATENT OFFICE

139,331,

DESIGN FOR A MILK BOTTLE

William C. Teunisz, Grand Rapids, Mich.

Application July 13, 1944, Serial No. 114,390

Term of patent 14 years

(Cl. D58—6)

To all whom it may concern:

Be it known that I, William C. Teunisz, a citizen of the United States, residing at Grand Rapids, county of Kent, and State of Michigan, have invented a new, original, and ornamental Design for Milk Bottles, of which the following is a specification, reference being had to the accompanying drawing, forming part thereof.

Figure 1 is a side elevational view of the milk bottle showing my new design.

Fig. 2 is a top view of the bottle shown in Fig. 1.

Fig. 3 is a side elevational view of the milk bottle, with the bottle rotated 45° from the position shown in Fig. 1.

The dominant features of my design reside in the portions shown in full lines.

I claim:

The ornamental design for a milk bottle, as shown and described.

WILLIAM C. TEUNISZ.
